UNITED STATES PATENT OFFICE.

AUGUST ARENS, OF NEW BRITAIN, CONNECTICUT, ASSIGNOR TO P. & F. CORBIN, OF SAME PLACE.

REVERSIBLE STORE-DOOR LATCH.

SPECIFICATION forming part of Letters Patent No. 286,250, dated October 9, 1883.

Application filed August 4, 1883. (Model.)

To all whom it may concern:

Be it known that I, AUGUST ARENS, a citizen of the United States, residing at New Britain, in the county of Hartford and State of Connecticut, have invented certain new and useful Improvements in Store-Door Latches, of which the following is a specification.

My invention relates to improvements in that class of latches in which a longitudinally-moving latch-bolt is drawn inward by means of a thumb-bar, said latches being known as "store-door" latches; and the objects of my invention are to provide a simple and cheap arrangement, in the form of a double angle-lever, for throwing the bolt, and to make the piece against which the thumb-bar presses changeably secured to said angle-lever, so as to project from either side of the case, to adapt the latch for use upon either a right-hand or a left-hand door. I attain these objects by the simple construction illustrated in the accompanying drawings, in which—

Figure 1 is a front elevation of my latch with the cap-plate of the case removed. Fig. 2 is a sectional view of the right-hand side of said latch, the plane of section being indicated by the line *x x* in Fig. 1; and Fig. 3 is a front elevation of parts of said latch.

A designates a longitudinally-moving latch-bolt, beveled at its outer end, and, if desired, provided with the anti-friction lever *a*. Said latch-bolt is forced inward under the influence of the keeper, upon closing the door, as in other latches, and it is forced outward by means of a suitable spring, *b*.

For the purpose of withdrawing the latch-bolt *A* from the keeper when the door is closed, I secure the horseshoe-shaped piece *B*, having suitable engaging-lugs, *c c*, to the inner end of the latch-bolt. I pivot to the case at *d* a T-shaped or double angle-lever, *C*, whose ends rest against the sides of the engaging-lugs *c c*, which face the latch-bolt, as shown, while the pivoted post *d* is upon the other side of said lugs and in longitudinal alignment with the latch-bolt. Upon the front face of the lever *C* are two stubs or posts, *h*, which are designed to receive, one at a time, the inner end of the vertically-moving slide *D*. Said slide is provided at its inner end with a hole of a suitable

size to fit and receive either of said posts *h*. The upper and lower side edges of the case are slotted or recessed to receive the body of the slide *D*, near its opposite end, and guide the same in its vertical movement. The lower end 55 of the slide *D* has a broad head, *k*, for the ordinary thumb-bars to act against in lifting the slide *D*. In view of the fact that this is a mortise-latch, the side walls of the case are brought nearer together in the vicinity of the slide than 60 elsewhere, thereby forming the notches *m* for the head *k* of the slide, and preventing said head from projecting so far beyond the main portion of the side edges of the case as to interfere with inserting the case endwise into a 65 mortise.

Instead of two posts *h h*, a single post may be placed on the lever *C*, intermediately between the present location of said posts, and then make the slide *D* correspondingly longer. 70

The lock is set in the position shown in the drawings, with the ordinary thumb-bars directly underneath the head *k* of the slides. By operating either thumb-bar in the ordinary manner it is pressed upward against the head 75 of the slide *D* and lifts said slide. The slide, being connected by the posts *h* to the lever *C*, necessarily imparts a swinging movement to said lever and forces the end of its upper arm against the upper lug of the horseshoe-shaped 80 piece *B*, to force said piece and the latch-bolt *A* inward into the position indicated for the respective parts by the broken lines in Fig. 1. So soon as the thumb-bar is released gravity restores the slide *D* and lever *C* to their normal positions, while the spring *b* projects the latch again. 85

If desired to place the latch the other side edge uppermost, for use upon a different-handed door, it is only necessary to remove the 90 cap-plate, lift the slide *D* from off the post *h* and out of its guiding-recess, and place it upon the lever *C*, with its head projecting from the other side edge of the case—that is, the edge opposite that from which it was last removed. 95

I am aware that store-door latches have been shown in prior patents as containing a vertically-moving slide at one edge of the case for being acted upon by the thumb-bars, said slide being secured to a pivoted angle-lever 100

which engaged a lug at the inner end of the latch-bolt; also, as containing a double angle-lever which acted upon engaging-lugs connected to the latch-bolt, the middle of which lever, for being acted upon by the thumb-bars, was arranged in the middle of an opening near the middle of the latch-case, to make the latch reversible; also, as containing a latch-bolt with a changeable engaging-lug and a changeable angle-lever, one arm of which was for being acted upon by the thumb-bars, the latch being reversed by changing the lug and angle-lever to either side; and, also, as containing a vertically-moving slide bearing a cam for acting upon the engaging-lug of the latch-bolt, and changeable, so that the end de-

signed to be acted upon by the thumb-bars may be projected from either side of the case for reversing. All of said prior art is hereby disclaimed.

20

I claim as my invention—

The combination of the latch-bolt having suitable engaging-lugs at its inner end, the double angle-lever, and the vertically-moving slide changeably secured to said angle-lever, substantially as described, and for the purpose specified.

25
AUGUST ARENS.
